[57] CLAIM

The ornamental design for a display stand for earrings, as shown and described.

DESCRIPTION

FIG. 1 is a front elevational view of a display stand for earrings showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and

FIG. 7 is a perspective view thereof.

FIGS. 5 and 6 have been shown on a reduced scale with respect to FIG. 1.
